UNITED STATES PATENT OFFICE.

LAWRENCE S. KASKIE, OF ROCK VALLEY, IOWA.

PUMPING MECHANISM.

1,158,228.

Specification of Letters Patent. Patented Oct. 26, 1915.

Application filed February 14, 1911. Serial No. 608,543.

To all whom it may concern:

Be it known that I, LAWRENCE S. KASKIE, a citizen of the United States, residing at Rock Valley, in the county of Sioux, State 5 of Iowa, have invented certain new and useful Improvements in Pumping Mechanisms; and I do hereby declare the following to be a full, clear, and exact description of the invention, such as will enable others skilled in 10 the art to which it appertains to make and use the same.

This invention relates to an improvement in horse cleaning devices, and has particular reference to cleaners of the type generally 15 known as vacuum cleaners.

The principal object of this invention is to provide a manually operated portable cleaner for the purpose described, which is composed of a minimum number of parts, 20 and is therefore simple in construction.

Another object of the invention is to provide a cleaner of the class described in which a novel construction of bag-holding means is employed.

With these and other objects in view, the invention consists in the construction and 25 novel combination of parts hereinafter fully described, illustrated in the accompanying drawings, and pointed out in the claim here- 30 to appended; it being understood that various changes in the form, proportion, size and minor details of construction, within the scope of the claim, may be resorted to without departing from the spirit or sacrificing 35 any of the advantages of the invention.

In the drawings: Figure 1 is a side elevation of the device, Fig. 2 is a longitudinal sectional view therethrough, parts of the 40 same being shown in elevation, Fig. 3 is a transverse sectional view taken on the line 3—3 of Fig. 2, and Fig. 4 is a detail end elevation with the operating levers removed, Fig. 5 is an enlarged sectional view of the clamping ring.

Like reference numerals designate corresponding parts in all the figures of the drawings.

Referring to the drawings, 5 designates an open ended cylindrical shell of any suitable material, and provided with a plurality of supporting feet 6—6 which are secured to a suitable base 6^a. Centrally formed in the top of the shell is an outwardly flared opening 7, and projecting from said shell 55 around the opening is a raised annular seat 8. A tapering annulus 9 is disposed within

said opening 7 and is of a shape corresponding thereto, the smaller end of said annulus being at the bottom. A laterally projecting flange 10 extends from the upper edge of 60 said annulus and a washer 11 is disposed between the seat 8 and the said flange. A clamping ring 12 is provided with an inclined outer edge 13, the exterior diameter of the ring being greater than the interior 65 diameter of the smallest or lower end of the annulus 9. A closely woven cloth bag 14 has its mouth disposed within the annulus, and secured thereto by the clamping ring 12 as will be readily understood. A concaved closure plate 15 is disposed above the opening, and is provided with a laterally projecting marginal flange 16 which is adapted to rest upon the flange 10 of the annulus. A washer 17 is preferably placed 70 intermediate the said flanges. Alined openings are respectively formed in the seat 8 and flanges 10 and 16. There may be as 75 many of these openings as desired, and associated with these openings are bolts 21, by means of which the closure plate 15 and the annulus 9 is secured to the cylinder 5. A nipple 22 extends outwardly from the closure plate 15 and communicates with the interior thereof. Secured to this nipple is 80 one end of a flexible pipe 23, the other end of the pipe being provided with a nozzle 24 having an elongated and narrow inlet opening 25.

Disposed within the cylinder 5, and on 85 either side of the opening 7, are partitions 26—26, by means of which a central air chamber 27 is formed. The fastenings of these partitions are located within the air chamber, as shown at 28. Bellows 28—28 are 90 respectively secured to the partitions, and extend outwardly toward the ends of the cylinder 5. Each of these bellows is provided with a head 29 having an ear 30 centrally secured thereto. Formed in each partition 26 and head 29 is a plurality of openings 31 and 32 respectively. Associated with the openings 31 are inwardly movable flap-valves 33, and associated with the openings 32 are outwardly opening flap-valves 34. 95

Secured to the base 6^a, and at either end of the cylinder 5, are floor-brackets 35—35, to each of which is pivotally connected an operating lever 36. Links 37 are respectively 100 and pivotally connected at their ends to the levers 36 and to the ears 30 carried by the heads 29 of the bellows. A coupling rod 38,

normally disposed above the cylinder, has its ends pivotally connected to the levers 36 as at 39—39. By reason of the fact that the partitions 26 have their fastenings located in the air chamber 27, these fastenings are accessible through the opening 7, for removal of the partitions in the event that repairs to the bellows are necessary.

From the foregoing, it will be observed that as either of the hand-levers 36 is oscillated, the bellows 28 will be alternately operated, one of the bellows drawing in air and the other exhausting the air brought in by the previous movement. It will be observed that as one of the bellows is expanded, air will be drawn in through the opening 25 of the nozzle 24, through the pipe 23, the closure plate 15, through the bag 14, through the openings 31, and into the bellows. Upon movement in the opposite direction of the lever, this air will be forced out through the openings 32, past the outwardly opening flap-valves 34, and into the atmosphere. It will also be observed that as the air passes through the bag 14, all foreign particles will be left within the bag. By this construction

a continuous suction is created. When the bag 14 has received a certain amount of dirt, the bolts 21 can be loosened and the bag removed.

What is claimed is:—

In a vacuum cleaner, the combination with a tubular cylindrical member having a cylindrical opening in the wall thereof, of spaced partitions within the casing on opposite sides of said openings respectively, said partitions having formed therein, outwardly opening valves controlling the openings in the partitions, air exhausting bellows secured to the outer faces of the partitions respectively, a lever pivotally mounted adjacent each end of the casing, a link connecting each lever with the adjacent bellows, and a link mutually connecting said levers whereby the movement of one will produce a corresponding movement of the other.

In testimony whereof, I affix my signature, in presence of two witnesses.

LAWRENCE S. KASKIE.
